UNITED STATES PATENT OFFICE.

GEDOR W. ALDEEN, OF ROCKFORD, ILLINOIS, ASSIGNOR TO NATIONAL LOCK CO., OF ROCKFORD, ILLINOIS, A CORPORATION OF ILLINOIS.

LOCK.

Application filed October 26, 1922. Serial No. 597,090.

This invention relates to locks of the detachable cylinder type which comprise a casing adapted to be inserted in a mortise formed in the edge of a drawer or the like, and a detachable cylinder adapted to be inserted from the front of the drawer through a round hole communicating with the mortise and to be detachably locked to the casing whereby the casing is held 10 against displacement from the mortise.

In locks of this general type, the key cylinder has been customarily provided with a longitudinally disposed key receiving slot which serves as the key guide, but since the 15 slot is open at one side there is a tendency, when the cylinder is positioned with the open side of the slot at the bottom, for the outer end of the key to drop so that it projects from the lock in a downwardly inclined position which is undesirable and unattractive. Furthermore the key cylinders themselves rotate in the hole bored for their reception and if the hole is not exactly straight, or is not made sufficiently larger 20 than the cylinder, binding between the periphery of the cylinder and the surrounding hole results which interferes with the operation of the lock. Another disadvantageous feature of such locks is that the 25 key may be inserted and withdrawn in any position of the cylinder and any length of key may be employed; consequently, the liability of opening the lock with an unauthorized key is rather great.

My present invention is designed to overcome the objections above noted to locks of this character by providing a lock which comprises a stationary key cylinder which, when attached to the lock case, remains in 30 fixed position instead of turning in the hole. A key guide is rotatably mounted in this cylinder and is retained therein by an in-turned flange at the end of the cylinder which is provided with a slot adapted to 35 align with the key receiving slot of the key guide when the guide is properly positioned. A key can, therefore, be inserted in the guide only when the guide is in one predetermined position and when inserted it is held by the surrounding cylinder in a 40 position perpendicular to the lock case and cannot drop or hang in an inclined unsightly position. Furthermore the slotted flange with which the key cylinder is 45 equipped necessitates the employment of a

key having a recess at a predetermined position on one edge which will align with and receive this flange when the key is properly positioned in the lock, thus permitting the key to be turned. This construction therefore necessitates the employment of a key which is not only properly shaped to actuate the tumblers, but is also provided with a recess at a predetermined position between its ends; consequently, the liability of the lock 60 being opened by the use of an unauthorized key is very materially reduced.

A further object of the invention is to provide novel means for detachably locking the key cylinder to the case and to provide 70 an ejector key for releasing this locking means which, by reason of its construction, may be employed for releasing cylinders of different lengths which may be required in different articles of furniture.

Other objects are to provide a lock which is simple in construction, economical to manufacture, easy to assemble, and one which will be reliable in operation and not 75 apt to get out of order.

Further objects and advantages of the invention will be readily appreciated as the same becomes better understood by reference to the following description when considered in connection with the accompanying 80 drawings.

Referring to the drawings:

Fig. 1 is a front elevation showing my improved lock applied to a piece of furniture;

Fig. 2 is a sectional view on the line 2--2 90 of Fig. 4;

Fig. 3 is a view similar to Fig. 2 with the cylinder locking tumbler removed, and showing the bolt actuating key in position in the lock;

Fig. 4 is a sectional view on the line 4--4 95 of Fig. 2;

Fig. 5 is a sectional view through the casing and cylinder showing the bolt actuating key in operative position;

Fig. 6 is a detail view of the ejector key;

Fig. 7 is a perspective view of the key cylinder with the key guide removed; and

Figs. 8 and 9 are front and rear views respectively of the lock, the key cylinder being removed in the front view.

Referring to the drawings, reference character 7 indicates a drawer front provided with a mortise adapted to receive the lock case 8 and with a hole intersecting said mor- 110

tise adapted to receive the key cylinder 9. The face plate 11 of the lock case is secured to the drawer front by screws 12 and is provided with an opening through which the locking bolt 13 may be projected.

The lock case comprises the back wall 14 and side walls 15 preferably formed integrally and a front wall 16 secured to the back wall by a plurality of studs 17, the ends of which project through the front wall 16 and are preferably riveted over to hold the parts together.

The locking bolt 13 is provided on one edge with an actuating slot 18 adapted to receive the bit 19 of the bolt actuating key 21 by which the bolt is projected into the locking position shown in Fig. 3 and retracted into unlocked position as shown in Fig. 2.

Upon the lower ends of the studs 17 there are pivotally mounted the bolt locking tumblers 22 and 23 and the cylinder locking tumbler 24, all of these tumblers being urged into locking position by springs 25. A detent 26 on the bolt is adapted to be engaged by shoulders 27 on the tumblers 22 and 23 to lock the bolt in projected position and by shoulders 28 on these tumblers which lock the bolt in retracted position. Upon swinging movement of the tumblers in a clockwise direction, viewing Figs. 2 and 3, they are released from the detent permitting actuation of the bolt. It will be observed from Fig. 5 that the bolt is actuated by engagement of the bit 19 in the slot 18, and that the bolt locking tumblers are actuated by the surfaces 29 and 31 on the key 21.

The key cylinder 9 is shaped as shown in Figs. 4, 5 and 7 so that the portion aligned with the lock tumblers is disposed entirely outside the case and lies against the front wall 16 of the case, whereas the remaining semi-cylindrical portion enters the case through an arcuate slot 32 formed in the wall 16 and is provided with projections 33 which extend through the rear wall 14 of the case. The uppermost portion of the cylinder projecting within the case is provided with a notch 34 adapted to receive the extension 35 formed on the cylinder locking tumbler 24 which is also pivoted on the stud 17 and is urged into locking position by one of the springs 25. When the cylinder is introduced into the casing, the inclined edge 37 of the cylinder forces the tumbler 24 to the right, viewing Figs. 2 and 4, thus permitting the full entrance of the cylinder into the case, whereupon the tumbler snaps into the notch or recess 34 locking the cylinder against withdrawal from the case.

Within the cylinder there is rotatably mounted a key guide 38 comprising the enlarged outer end adapted to fit in the groove 39 formed near the outer end of the cylinder 9; the metal of the cylinder outside the

head being bent inwardly to provide a flange 41 which retains the key guide against displacement. The stem 42 of the key guide is provided with a key receiving slot 43 and its inner end is reduced as indicated at 44 and is adapted to project through an aperture 45 formed in the rear wall 14 of the case in alignment with the longitudinal axis of the key cylinder.

In assembling the lock, the case is first set in the mortise whereupon the key cylinder is inserted through the hole which intersects the mortise, and when fully inserted in the position shown in Figs. 4 and 5, it is locked against withdrawal by the cylinder tumbler 24 and is held against rotation by the projecting prongs 33 while the key guide is centered and a bearing is afforded for its rear end by the opening 37 through which it projects.

The slot 43 of the key guide extends through the enlarged head thereof for the reception of a key at its outer end, and the key guide retaining flange 41 formed on the outer end of the cylinder is provided with a slot or notch 46 with which the slot 45 is adapted to align when the guide is rotated into a predetermined position as shown in Fig. 1. When the key 21 is to be inserted in the guide, the insertion can be accomplished only when the slot 45 is aligned with the notch 46, and in order to permit of rotative movements of the key, it is provided at the proper point between its ends with a recess 47 adapted, when the key is fully inserted as shown in Fig. 5, to register with the cylinder flange 41 to permit rotative movement of the key for the purpose of releasing the bolt locking tumblers and manipulating the bolt. Since the key cylinder remains stationary during rotative movements of the key and is firmly supported at opposite ends on both the front and rear walls of the lock case, it will be apparent that there is no possibility of binding or cramping the movements of the key as frequently occurs in those detachable cylinder locks in which the cylinder itself revolves in the hole in which it is mounted. Furthermore, the cylinder prevents the outer end of the key from dropping or sagging when the key remains in the lock and holds it in horizontal position so that it presents a neat appearance. It should also be noted that the lock cannot be manipulated except with a key which is provided with a recess 47 located at the proper position on the shank of the key which feature greatly reduces liability of the lock being operated by an unauthorized key.

For the purpose of releasing the cylinder from the case to permit its withdrawal when occasion requires, my invention contemplates an ejector key, designated generally by reference character 48. The inner end

of this key is flat, as indicated at 49, and is of sufficient width to engage the projection 35 on the cylinder locking tumbler 24, whereby upon rotation of the key in a clockwise direction viewing Fig. 2, this tumbler is released so as to permit withdrawal of the cylinder. The cylinders are necessarily made in various lengths to accommodate the lock to drawer fronts or other furniture parts of various thickness, and in order that one ejector key may serve to release the cylinder locking tumbler of any length of cylinder, its edges are provided with recesses 49 and 51 respectively disposed in staggered relation and spaced apart one-eighth of an inch on each edge thereby making the key adaptable to operate the cylinder tumbler of any lock, since the cylinders themselves differ in lengths by sixteenths of an inch one from another.

While each lock therefore can be manipulated only by a key cut to fit the same and having its recess 47 disposed at the proper position on the shank of the key, any of the locks of this type can be actuated to release the cylinder and permit its withdrawal by the use of one ejector key 48, thus making it unnecessary to manufacture a special ejector key for each lock.

It is believed that my invention and many of its attendant advantages will be understood and appreciated from the foregoing, and while I have shown and described a preferred embodiment of the invention, obviously the details thereof may be varied within wide limits without exceeding the scope of the invention as defined in the following claims.

I claim:

1. In a lock, the combination of a lock case, a key cylinder non-rotatably but detachably connected to said case, a key guide rotatably mounted in said cylinder, and a tumbler for releasably locking the cylinder in position on the case.

2. In a lock, the combination of a lock case, a key cylinder, a key guide rotatably mounted in said cylinder and adapted to receive a key only when disposed in one predetermined position in the cylinder, and a tumbler for detachably securing said cylinder to said case.

3. In a lock, the combination of a lock case, a key cylinder having one end projecting into the case and supported at its outer and inner ends on the front and rear walls of the case and equipped at its outer end with an inwardly-extending flange provided with a radial slot, a key guide rotatably mounted in said cylinder and provided with a key receiving slot adapted to be aligned with said cylinder flange slot for the reception of a key, and means for detachably connecting the cylinder to the case.

4. In a lock, in combination, a case, a key cylinder non-rotatably but detachably connected to the case, a tumbler for locking the cylinder in the case against withdrawal, a key guide rotatably mounted in the cylinder, and a key adapted to be inserted into the key guide and to be turned for displacing said tumbler for permitting withdrawal of the cylinder.

5. In a lock, the combination of a case, a key cylinder projecting through said case at spaced intervals so as to be held against rotation, a tumbler in such case adapted to engage said cylinder to lock the same against withdrawal from the case, said cylinder being provided at its outer end with an inwardly extending flange having a radially disposed slot, a key guide rotatably mounted in said cylinder and provided with a key receiving slot adapted to be aligned with said key cylinder flange slot, and an ejector key provided with recesses on its opposite edges arranged in staggered relation and adapted to receive said flange on cylinders of various lengths, said key being adapted upon rotation to release said tumbler thereby permitting withdrawal of the cylinder from said case.

6. In a lock, the combination of a case, having a semi-circular opening in one wall thereof adapted to receive a cut-away key cylinder and having spaced openings in the opposite wall thereof to receive projections of said cylinder whereby the cylinder is held against rotation relatively to the case, a tumbler in said case adapted to engage said cylinder and lock the same against withdrawal, a slotted key guide rotatably mounted in said cylinder, said lock being adapted to be operated by a key of a predetermined length, and an ejector key operable in cylinders of various lengths for releasing said cylinder locking tumbler.

7. In a lock, in combination, a lock case, a non-rotatable key cylinder, a locking bolt, and a plurality of tumblers concentrically pivoted within the case including a bolt-locking tumbler and a cylinder-locking tumbler.

8. In a lock, in combination, a lock case, a key cylinder non-rotatably but detachably supported on the case, and a tumbler for locking the cylinder in position on the case and adapted to be displaced for permitting detachment of the cylinder.

9. In a lock, in combination, a lock case, a key cylinder, the case being shaped to receive and hold the cylinder against rotation, and a tumbler for holding the cylinder from axial displacement.

10. In a lock, in combination, a lock case, a key cylinder, a rotatable key guide within said cylinder, and a spring-pressed tumbler adapted for locking the cylinder to the case and to be displaced against its spring pres-

- sure for permitting withdrawal of the cylinder from the case.
11. In a lock, in combination, a lock case, a key cylinder non-rotatably but detachably supported on both the front and rear walls of the case, and means within the case for locking the cylinder thereto upon assembly of the cylinder and case and adapted to be displaced for withdrawal of the cylinder from the case.
12. In a lock, in combination, a lock case, a key cylinder non-rotatably but detachably supported on both the front and rear walls of the case, and means within the case for detachably engaging the cylinder when it is supported on said front and rear walls for locking it in position thereon.
13. In a lock, in combination, a lock case, a key cylinder non-rotatably but detachably supported on both the front and rear walls of the case, and a tumbler within the case for locking the cylinder in position.
14. In a lock, in combination, a lock case, a tumbler pivot pin supported at opposite ends on the front and rear walls of the case, a locking bolt in the case, a plurality of spring-pressed tumblers pivoted on said pin including a bolt-locking tumbler and a cylinder-locking tumbler, and a key cylinder adapted to be inserted at one end into the case and to be locked therein against rotation by said cylinder-locking tumbler.
15. In a lock, in combination, a lock case, a key cylinder adapted to be inserted through the front wall of the case and to be supported on both the front and rear walls thereof, a key guide rotatably mounted in the key cylinder, and a plurality of locking tumblers in the case one of which is adapted for locking the cylinder against withdrawal therefrom and is adapted to be displaced by operation of a key in the key guide for permitting removal of the cylinder.
16. In a lock, in combination, a lock case having a cylinder receiving and supporting opening in one wall and a cylinder supporting recess or the equivalent on its opposite wall, a key cylinder, one end of which is adapted to be passed through said opening and to fit in said recess, whereby the cylinder is non-rotatably supported on opposite walls of the case, and means for detachably connecting the cylinder to the case.
17. In a lock, in combination, a lock case, a key cylinder cut away at one end providing an inclined face and a lock-receiving notch, the case having an opening in its front wall to receive the cutaway end of the key cylinder, a spring-pressed locking part in the case normally over-reaching said opening and adapted to be displaced by said inclined face upon insertion of the cylinder and to snap into said notch for locking the cylinder against withdrawal, and means supporting the inserted end of the key cylinder on the rear wall of the case.
18. In a lock, in combination, a lock case having an arcuate opening in its front case having an arcuate opening in its front and its rear wall, a key cylinder cut away on one side part way of its length leaving a cylindrical end portion, the cutaway end of the cylinder being adapted to be inserted lengthwise through the opening in the front wall and having a reduced end adapted to fit in the opening in the rear wall, the cutaway end of the cylinder having a lock-receiving recess, and a locking member in the case adapted to enter said recess for locking the cylinder in the case.
19. In a lock, in combination, a lock case having an opening through its front wall including an arcuate portion, a key cylinder cut away at one end part way of its length leaving a cylindrical key-receiving end, a spring-pressed locking part in connection with the case normally over-reaching said arcuate portion of the case opening, the cutaway end of the key cylinder being adapted to be inserted through said opening and to displace said part, which is adapted to snap into locking engagement with the key cylinder for preventing its withdrawal, and the key cylinder when in said locked position being held against rotation by contact with the ends of said arcuate slot portion.
20. In a lock, a lock case for insertion in a mortise and having a cylinder receiving slot in both front and rear walls thereof, a hollow shell-like cylinder adapted to enter said slots and to be held against rotation thereby, and key operable means for releasably locking said cylinder in position in said case.
21. In a lock, a key cylinder having a cylindrical outer section, a substantially semi-cylindrical intermediate section providing a shoulder in conjunction with the outer section, a reduced inner section, and a recess in one of the latter two sections; the shoulder formed by the juncture of the outer and intermediate sections being adapted to axially position the cylinder in a lock case, the intermediate section being adapted to be supported on the rear wall of the case, and the recess being adapted to receive a tumbler within the case to lockingly interengage the lock case and cylinder.
22. In a mortise lock, a lock case having front and rear walls, a key cylinder engaged by said front and rear walls against rotation, and means automatically operative upon insertion of said cylinder within said case for cooperative engagement with the cylinder to retain it against displacement from the case.
23. In a mortise lock, a lock case having front and rear walls, a key cylinder engaged

by said front and rear walls against rotation, means automatically operative upon insertion of said cylinder within said casing for retaining said cylinder against displacement, and a key guide rotatably mounted within said cylinder.

24. In a lock, a lock case having front and rear walls, a key cylinder engaged by said front and rear walls against rotation, means automatically operative upon insertion of said cylinder within said casing for retaining said cylinder against displacement,

ment, and a key guide rotatably retained within and by said key cylinder.

25. In a lock, a walled casing, a key cylinder having a portion adapted to be non-rotatively engaged and positioned by one wall of the casing and having a shoulder portion adapted to engage another wall of the casing to axially position said cylinder with respect to said casing, and rotatable means connected with said cylinder for guiding a key within said cylinder.

GEDOR W. ALDEEN.
